UNITED STATES PATENT OFFICE

117,706

DESIGN FOR A COMPACT CASE

Charles Amick, Topeka, Kans.

Application March 18, 1938, Serial No. 75,925

Term of patent 3½ years

To all whom it may concern:

Be it known that I, Charles Amick, a citizen of the United States, residing at Topeka, in the county of Shawnee and State of Kansas, have invented a new, original, and ornamental Design for Compact Cases, of which the following is a specification, reference being had to the accompanying drawing, forming part thereof.

Fig. 1 is an open plan view of a compact case, showing my new design. Fig. 2 is a top plan view of the case when closed. Fig. 3 is a sec-

tional view taken on line 3—3 in Fig. 2. Fig. 4 is an end elevational view thereof.

The design is characterized by the three diagonally disposed receptors shown on the lefthand side of the case in Fig. 1, in combination with the compact case shown.

I claim:

The ornamental design for a compact case, as shown and described.

CHARLES AMICK.
